UNITED STATES PATENT OFFICE.

WILLIAM JAMES HINES, OF LEOMINSTER, MASSACHUSETTS, ASSIGNOR TO PURITAN COMB COMPANY, OF LEOMINSTER, MASSACHUSETTS, A CORPORATION OF MASSACHUSETTS.

HINGE FOR CELLULOID ARTICLES.

1,160,984.

Specification of Letters Patent. Patented Nov. 16, 1915.

Application filed April 30, 1914. Serial No. 835,555.

To all whom it may concern:

Be it known that I, WILLIAM J. HINES, a citizen of the United States, residing at Leominster, in the county of Worcester and 5 State of Massachusetts, have invented a new and useful Hinge for Celluloid Articles, of which the following is a specification.

This invention relates to a hinge for celluloid articles, such as tooth-brush holders, 10 toilet cases, and the like, but is capable of general use.

The principal objects of the invention are to provide an inexpensive hinge which will not involve the boring or drilling of the 15 members to be connected together, in which the hinge pin itself will be rendered invisible, and by which the celluloid articles to be connected will be reinforced at the edges which are connected by the hinge.

20 The invention also involves other advantages as will appear hereinafter.

Reference is to be had to the accompanying drawings in which—

Figure 1 is a plan of a preferred embodiment of the invention; Fig. 2 is a similar view with the parts separated and ready to be assembled; Fig. 3 is a plan of the blank for producing one of the hinge members; Fig. 4 is a plan of a blank for producing the 30 other hinge member; and Fig. 5 is an enlarged sectional view on the line 5—5 of Fig. 1.

The hinge is shown as used for connecting two flat celluloid members A and B. 35 These are connected by two hinge pieces C and D and a hinge pin E. The two hinge pieces C and D are formed by stamping out pieces of sheet celluloid in the forms indicated in Figs. 3 and 4. The piece C is rectangular in shape, and is provided with two 40 rectangular openings c therein equally spaced from the ends. The member D is of the same size and shape as the member C but is provided with a central opening d 45 therein of the same width as the openings c and of a length equal to the distance between the openings c. At the ends of this opening d are two spaces of the same length as the openings c and beyond them are a 50 pair of notches d' of the same width as the openings d and extending to the end of the piece D. It will be seen, therefore, that if one of these members is placed on the other there will be a space through the center of 55 each in which the openings and notches of

each member register with the solid parts of the other member both in width and length. In the formation of the hinge these two members are both doubled on a longitudinal central line in such a way that the flanges 60 which are formed by their edges are at a distance apart equal to the thickness of the members A and B. This forms loops of the solid parts of each of the members C and D at the center. In order to connect these two 65 parts together the hinge pin E is passed through these loops as is clearly shown in Fig. 2. This hinge pin is made of a length less than the height or length of the hinge members. This hinge piece consisting of 70 these three members C, D and E can be made as a separate article of manufacture and sold to the parties who desire to use them to be assembled in such way as may be desired, but preferably it is applied directly 75 to the article on which it is to be used. For that purpose the member A is applied to the member D so that its edge extends into the space between the flanges and abuts against the convex portions of the member C which 80 are on that side of the hinge pin. The contacting surfaces of the members A and D are cemented together so as to form a complete body of which the hinge member is a 85 solid part.

The member B is provided with two projections b at the ends, the distance between these being equal to the length of the hinge pin E. This being prepared it is then applied to the member C in the way which has 90 been described with reference to the members A and D. In this way the complete article is assembled as shown in Figs. 1 and 5, and a hinge is secured in which the hinge pin is entirely concealed and no metallic 95 part comes to view at any point, yet the assembling is extremely simple and expeditious, so that the complete article can be produced at low expense. The hinge pieces also constitute reinforcements of the edges 100 of the members A and B being cemented to them all along these edges. This is an important feature also because these are the edges which with other forms of hinges receive the hardest wear and give out first, but with this invention the hinge is the most durable part of the device. It will be understood, of course, that for producing finished articles the edges of the members C and D are preferably beveled or rounded 110

before being applied as indicated in the drawings.

Although I have illustrated and described only a single embodiment of the invention, 5 I am aware of the fact that it can be carried out with modifications and that it can be applied to many other articles and made of other materials than those specifically mentioned. Therefore, I do not wish to be 10 limited in these respects, but

What I do claim is:—

1. As an article of manufacture a hinge comprising two hinge members, each having 15 openings and solid spaces, said pieces being doubled over and placed together so that the projections on one enter the openings on the other, a hinge pin passed through the loops thus formed and terminating at a distance inside the ends of said members, the flanges 20 of one of said members produced by doubling over being spaced from each other, and a member to be connected by said hinge having its edge inserted between said flanges, and means whereby the ends of the hinge 25 pin are concealed.

2. As an article of manufacture a hinge comprising two hinge members of sheet

celluloid, one having a plurality of central longitudinal openings and the other having solid spaces registering with said openings 30 and being cut out at all other points in its length along the center, said pieces being doubled over on a longitudinal central line and placed together so that the projections 35 on one enter the openings on the other, a hinge pin passed through the loops thus formed and terminating at a distance inside the ends of said members, and two members to be connected by said hinge, said latter members having their edges inserted between the flanges of said members and cemented to the inner surfaces thereof 40 throughout the area of the flanges and one of said members being provided with projections at the ends spaced apart, whereby 45 said projecting ends conceal the ends of the hinge pin.

In testimony whereof I have hereunto set my hand, in the presence of two subscribing witnesses.

WILLIAM JAMES HINES.
